UNITED STATES PATENT OFFICE.

CLEMMIE JANE WARD, OF LESTER, WEST VIRGINIA.

DESIGN FOR A BANNER.

53,950.

Specification for Design.

Patented Oct. 7, 1919.

Application filed March 16, 1918. Serial No. 222,987. Term of patent 7 years.

To all whom it may concern:

Be it known that I, CLEMMIE JANE WARD, a citizen of the United States, residing at Lester, in the county of Raleigh and State of West Virginia, have invented a new, original, and ornamental Design for Banners, of which the following is a specification, reference being had to the accompanying drawing, forming a part thereof.

The figure is a view showing my new design.

I claim:

The ornamental design for a banner as shown.

CLEMMIE JANE WARD.

Witnesses:

CYNTHIA CANADAY,

W.M. R. PARSONS.
